UNITED STATES PATENT OFFICE

JACQUE C. MORRELL, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

REFINING OF GASOLINE-LIKE PRODUCTS OF HYDROCARBON OIL CONVERSION

No Drawing. Continuation of application Serial No. 74,398, filed December 9, 1925. This application filed October 31, 1929. Serial No. 403,913.

This application is a continuation of my copending application, Serial No. 74,398, filed December 9, 1925.

This invention relates to improvements in

- 5 the refining of the gasoline-like products of hydrocarbon oil conversion, and refers more particularly to the treatment of the lighter gravity overhead condensed products obtained from the cracking or distillation of 10 petroleum oil with treating agents for the purpose of removing or converting color-forming, odoriferous, sulphur and other objectionable compounds contained therein to 15 produce substantially water white, stable products which will satisfy commercial requirements.

The present invention specifically contemplates the addition of sulphur dioxide to sulphuric acid for use as a refining agent. I am 20 well aware that heretofore petroleum oils have been refined by using sulphuric acid as well as the use of liquified sulphur dioxide, but I believe I am the first to combine sulphur dioxide with sulphuric acid and utilize 25 the product thus obtained as a refining agent.

The action of sulphuric acid upon certain types of cracked oils is such as to produce undesirable color-forming and odor-forming substances in addition to its refining action.

30 The presence of sulphur dioxide prevents this action.

As a specific example of the preparation of the reagent made use of in this invention, sulphur dioxide (a gas) is passed into the 35 body of sulphuric acid until the latter is saturated with the sulphur dioxide. Sulphuric acid will absorb a large percentage of sulphur dioxide without an appreciable increase in volume, although in the completely saturated state there is an increase in volume of the sulphuric acid. It is not necessary, however, to completely saturate the sulphuric acid with sulphur dioxide in order to obtain 40 the beneficial effects owing to its presence.

45 With certain types of oils, the sulphuric acid combined with sulphur dioxide may be used as a sole refining agent, the traces of the acid, of course, being removed with alkali, if desirable.

50 With other types of oils, it may be advis-

able to supplement the refining action of the sulphuric acid and sulphur dioxide by also separately subjecting the oil to the action of other refining reagents, for instance, plumbite, copper salts in solution, earthy adsorbents, and the like, and the invention is not limited to any particular order or succession of use for these refining reagents it being within the determination of the skilled operator to subject the oil to these reagents in proper succession to secure the most advantageous results in an economical manner.

The invention is more particularly directed to the refining of those overhead condensed products having an end boiling point 65 requiring no further distillation and produced as a direct product of the cracking process, as well as those lighter gravity overhead products which require further distillation.

70 The following are the claims:

1. The method of refining cracked hydrocarbon distillates which comprises subjecting the same to the action of sulphuric acid saturated with sulphur dioxide.

75 2. The method of refining hydrocarbon oil which comprises subjecting the same to the action of sulphuric acid saturated with sulphur dioxide.

80 In testimony whereof I affix my signature.

JACQUE C. MORRELL.
